IGNITION SHIELDING

Joseph J. Mascuch, Newark, N. J.

Application July 11, 1931, Serial No. 550,076

20 Claims. (Cl. 123—148)

This invention relates to means for shielding the ignition system of internal combustion engines and is a continuation in part of application Serial No. 394,618, filed September 23rd, 1929.

5 One object of the invention is to provide a conduit system for ignition which will completely isolate, electrically, the ignition system of an internal combustion engine.

When internal combustion engines using electrical ignition systems are used in proximity to radio receiving apparatus, there is a radiation of electrical waves from the ignition system, which radiation causes interference with the reception of radio equipment.

10 15 By properly surrounding with a conductive casing, all of the parts of the ignition system through which high frequency currents pass and grounding the said conducting casing, it is possible to dissipate the energy of the electrical radiations directly to ground, thereby preventing the aforementioned interference. It is an object of this invention to provide a conductive casing or shielding for the entire ignition system of internal combustion engines, whereby interference to radio communication and equipment installed in proximity to the engine will be eliminated.

20 25 This invention is applicable to all types of combustion engines and particularly to engines on units such as aeroplanes, motor boats, automobiles, submarines, etc. For the purpose of illustrating and describing the invention only its application to a radial aeroplane engine is shown. However, this is not to be construed as a limitation of the uses of the invention. The invention may also be used on stationary engines.

30 35 In order to provide an effective shielding means it is necessary to shield the low and high tension conductors, the starting and switch circuits, the spark plugs, magnetos, distributors, generator, and battery, or any other means for the production and distribution of electrical energy that may be used. All of the electrical equipment is insulated. The shielding is accomplished by enclosing all of the electrical equipment in highly conductive casings or shields which are grounded or bonded to the engine and fuselage of the aeroplane so that any electrical radiation will be absorbed and grounded by the shields.

40 45 Due to the extreme conditions under which an aeroplane engine operates it is necessary, in order to have an effective shield, that the ignition system be protected from the possibility of failure due to outside interference. A short circuit or break in any part of the ignition system will cause most serious damage. Oil, water or gaso-

line will deteriorate the insulating material, at first permitting corona discharges and eventually resulting in a total breakdown of the insulation, thereby causing the necessity for the replacement of the defective conductor. Therefore, another object of the invention is to provide a shielding means for the ignition system which will prevent water, oil, gas or other detrimental foreign substances from reaching the conductors or other parts of the ignition system, and which, by enclosing the entire system in a fireproof casing will minimize the risk of fire caused by short circuits, resistance flashes and sparking.

5 10 15 In order for a shielding system to be practical it must be constructed so that it may be easily applied to an engine and constructed so that parts thereof may be removed or replaced without the necessity of dismounting the engine and removing the entire shielding means. In the past, shields applied to aeroplane engines have been placed on the rear of the engine and have not been built in sections. In order to either apply or service the shielding system it has been necessary to practically dismount the engine and the shielding means. Therefore, another object of the invention is to provide a shielding system which may be easily and quickly applied to the front of the engine behind the propeller, without the necessity of disturbing the engine, and which may be made in sections so that any part may be 20 25 easily and quickly removed and another part substituted without removing the entire shielding means. By placing the shielding means immediately behind the propeller it is subject to blast of the propeller which prevents the accumulation of oil, water, or other detrimental foreign substances on the shields. A further object of the invention is to make the joints or connections of such sections thoroughly water and oil proof so that no moisture or other detrimental agents can get into the shielding means.

30 35 40 45 A further object of the invention is to provide a main manifold from which sub-conduits lead to the individual spark plugs and magnetos. In the past, in shielding the conductors it has been common practice to directly shield each lead from the magneto to the spark plug, thereby increasing the capacitance between the ignition conductor and ground, thereby reducing the intensity of the spark, resulting in a loss of power or failure of the compressed charge to ignite, thereby charging the exhaust manifold with an explosion maximum which subsequently explodes in the manifold, greatly increasing the fire hazard. Since the primary wiring of the mag-

50 55

netos is grounded and the shielding is grounded, the greater the length of the shielding the more resistance will be set up in the magnetos. If this resistance rises to a point where the magnetos are 5 not strong enough to overcome it, the engine will miss. By using a single main manifold for all the wires the capacitance of the shielding system is decreased and the resistance in the magnetos materially reduced.

10 Where rigid shielding is used the vibration causes rapid wear and abrasion of the insulating materials of the conductors. As soon as the insulation is damaged electrical emanations are released therefrom with resultant loss of power 15 and efficiency. Therefore, a further object of the invention is to provide flexible conduits to the spark plugs and magnetos so that the harmful effects of vibration will be minimized. This insures longer wear and less likelihood of break- 20 down. Where rigid shielding is used the vibration causes the shielding to crystallize and break. By using flexible shielding this danger is eliminated.

In high tension conductors it is essential that 25 the outer surface of the insulating material be smooth and that the conductor be kept free from kinks or sharp bends at which points charges of high potential may build up. In case the smooth or lacquered surface of the insulation becomes 30 damaged at points or sharp bends, the accumulated charge will create a corona discharge from the rough or fuzzy points, thereby gradually deteriorating the entire insulating material and causing a complete break-down of the insulation 35 at this point, resulting in a short circuit. By making the inside of the conduits smooth, the lacquer finish of the conductors is not damaged when they are drawn through the conduits. It is therefore a further specific object of the invention 40 to provide a shielding means wherein the inner surface of the conduits will be smooth and wherein the outlets from the main conduit will be curved so that sharp bends and kinks in the conductors will be impossible. By making the 45 conduits larger than the conductors an air gap will be left in the conduit around the conductors. This air gap increases the insulation and also prevents, to a certain extent, wear and abrasion 50 of the conductors.

50 At high altitudes or under other conditions of low atmospheric pressure, at which time the conduction of the surrounding air is very much greater than the conduction of the compressed gas between the gap of the spark plug points, 55 there is danger of the ignition current flashing over or sparking to a nearby grounded conductor and natural sparking outlet at spark plug points. It is standard practice to maintain a distance of at least $\frac{5}{8}$ ths of an inch between any uninsulated 60 conductor carrying ignition current from any grounded part. In providing a shielding means for the spark plug, it would be necessary to use a large and bulky grounded conductor to enclose the spark plug, unless other insulating means is 65 provided. It is therefore a further specific object of this invention to provide a shielding means of moderate size for the spark plug which will provide a distance of at least $\frac{5}{8}$ ths of an inch between all uninsulated parts carrying high tension 70 ignition current from surrounding grounded parts. Changes of temperature will cause condensation of moisture on the insulating body of the spark plugs and snow, water or ice which may leak through the shielding means and gather 75 on the insulated body of the spark plug will cause

a short circuit and make it extremely difficult to start the engine without first wiping off all moisture from the insulated body of the spark plug and spark plug leads. It is therefore a further specific object of this invention to provide a 5 waterproof and air tight shielding means for the spark plugs.

The invention consists of the construction, combination and arrangement of parts as herein illustrated, described and claimed. 10

In the accompanying drawings, forming part hereof, is illustrated a form of embodiment of the invention, in which drawings similar reference characters designate corresponding parts, and in which:

15 Figure 1 is a front elevation of a radial aircraft engine, showing the application of the invention thereto;

Figure 2 is a fragmentary detail in side elevation showing one conduit to the spark plug on 20 the rear side of the engine;

Figure 3 is a rear elevation of a shielding system, showing the main manifold with the flexible conduits extending therefrom;

Figure 4 is a fragmentary detail in elevation, 25 partly in section, showing the connection between the parts of the main manifold;

Figure 5 is a rear elevation of a coupling means to the magneto, showing part of the magneto covers; 30

Figure 6 is a side elevation, partly in section, of the couplings shown in Figure 5;

Figure 7 is a fragmentary detail, partly in section, showing the method of attaching the main manifold to the crankcase;

Figure 8 is a composite plan view, partly in section, showing one outlet from the main manifold and one type of shielded spark plug;

Figure 9 is a front elevation, partly broken away, of a spark plug shield;

Figure 10 is a vertical section taken approximately on line 10—10 of Figure 9, looking in the direction indicated by the arrows;

Figures 11 and 12 are fragmentary details showing the method of holding the conduits to the 45 engine;

Figure 13 is a horizontal section on line 13—13 of Figure 12, looking downward;

Figure 14 is an enlarged detail, partly broken away, showing the structure of the flexible conduit; and,

Figures 15 and 16 are diagrammatic plan views of modified systems of wiring showing the use of a junction box.

Referring to the drawings 21 designates the 55 crankcase of an aircraft engine having radial cylinder blocks 22 extending therefrom. The cylinder blocks 22 carry push-rod casings 23 and the propeller 24 is carried on the center of the crankcase 21. Disposed on the crankcase 21 is 60 a two-piece manifold 25. The manifold 25 may be of any shape or contour desired to fit any particular engine, such as oval, straight, round, etc. The manifold 25 is here shown as being made in two parts but it may be made in one or several parts as necessity or efficiency dictates. The manifold 25 consists of a metallic tube having closed ends, and having a smooth interior and exterior finish.

One section of the manifold 25 is provided 70 with a flange 26 and the other section of the manifold 25 is provided with a screw-threaded portion 27. A collar nut 28 is provided to hold the two sections of the manifold 25 together and a metal gasket 29 is disposed between the two 75

sections to insure a tight closure and to insure a good electrical contact. It will be borne in mind that all connections in this invention must be both liquidproof and made so as to form a continuous electrical conductor.

The manifold 25 is secured to the crankcase 21 by means of brackets 30. The brackets 30 may be disposed at any point around the manifold 25. The brackets 30 are silver-soldered to the manifold 25. While the brackets 30 may be secured to the manifold 25 in any suitable manner it has been found that the use of silver solder is more efficient, giving a stronger bond for the weight of solder used and leaving a smooth surface to prevent the accumulation of dirt, etc. The brackets 30 are provided with openings 31 through which studs 32 are disposed to hold the manifold 25 to the crankcase 21, as best shown in Figure 7.

Disposed around the manifold 25, on the outside thereof, are outlets 33, for the purpose of leading the ignition wires to the spark plugs. The outlets 33 may be made as a part of the manifold 25 but also may be made separately and silver-soldered to the manifold 25. The outlets 33, as best shown in Figure 8, comprise a tubular body 34, the center line of which extends outward at right angles to the manifold 25.

The manifold end of each member 34 is flared outward on one side at 35. The opposite side 36 describes a longer curve before reaching the manifold 25. The purpose of this curved section 36 is to eliminate the sharp bend otherwise necessary in the ignition wire when passing from the manifold 25 through the outlet 33. An additional advantage of the curved portion 36 is that it indicates in which direction a wire will run in the manifold 25, thus assisting in arranging the proper assemblage of the ignition wires. The other end of the tubular member 34 is provided with a screw-threaded section 37. On the inside, adjacent the outer end, the member 34 is provided with a beveled face 38 for the purpose hereinafter described.

The ignition wires or conductors 39 are encased in insulation 40 and pass from the manifold 25 through the outlet 33 to the spark plugs. Disposed around the conductors 39 between the outlets 33 and the spark plugs are conduits 41. The conduits 41 are secured to the outlets 33 by means of interiorly screw-threaded collar nuts 42.

The conduit 41 is fabricated from three layers of material, as best shown in Figure 14, the inner layer being formed of a single continuous strip of metal 44 spun upon itself to produce a flexible housing for the conductors 39 and insulation 40. The strip 44 may be made of any suitable metal but is preferably made of aluminum. The strip 44, in cross-section is substantially the shape of a block letter S and is so spun as to provide oppositely disposed interlocking flanges 45. When the strip 44 is spun a packing 46 is introduced between the flanges 45. The packing 46 may be asbestos and is saturated with graphite to insure a good conducting element through the strip 44. When the inner conduit has been spun as described air spaces 43 are left between the flanges 45, thus leaving room for flexing the conduit 41.

With this construction the inside surface 47 of the conduit 41 is made perfectly smooth so that when the conductors 39 with the insulation 40 are drawn through the conduit 41, the lacquer finish on the insulation 40 will not be damaged.

Even though the conduit 41 be bent or flexed the

inner surface 47 will still be smooth and thus preserve the insulation 40. As pointed out heretofore if the insulation 40 is damaged in any way a loss in efficiency in the ignition system will result. The inside of the conduit 41 is larger than the conductor 39 with its insulation 40. This leaves an air gap inside the conduit 41 which greatly increases the insulating qualities and prevents abrasion of the insulation 40.

Disposed around the inner conduit formed by 10 the strip 44 is a jacket or casing of braided wire 48. Many types of wire may be used but it has been found highly successful to use a braiding of fine-gauge tinned copper wire. On the outside of the conduit 41 is braided a protective casing 15 or armor 49 composed of strips of metal or flat wire. The function of the armor 49 is to both protect the conductor 39 and act as an electrical conductor. Therefore, many types of armor may be used. However, it has been found that for 20 flexibility, durability, strength and lightness, an armor made of phosphor bronze ribbon is highly successful. With this construction a continuous electrical bond is made between the layers of 25 the conduit 41.

Disposed on each end of each conduit 41 is a ferrule 50. The outer end 51 of the ferrule 50 is crimped or spun against the armor 49 to hold the strips of the armor 49 from movement and to insure a good electrical contact. The center 30 portion of the ferrule 50 is formed into an outwardly extending flange 52 by means of bending the ferrule 50 upon itself. The inner end 53 of the ferrule 50 covers the ends of the armor 49, the braid 48 and the strip or inner conduit 44, 35 and is turned inwardly in the conduit 41. The inner end 53 is pressed against the inside 47 of the conduit 41 so as to eliminate any raw edges and to present a smooth orifice for the conductor 39.

Disposed around the insulation 40 of the conductor 39 is a conical rubber washer 54. When a conduit 41 is connected to an outlet 33 the washer 54 strikes the beveled face 38 of the outlet 33 and the flange 52 of the ferrule 50 presses 45 against the opposite face of the washer 54. The collar nut 42, when screwed onto the threads 31, forces the flange 52 against the washer 54, the conical face of which is forced against the beveled face 38 of the outlet 33 and makes a waterproof connection. When the washer 54 is thus held under pressure it holds the insulation 40 of the conductor 39 to the center of the outlet 33, thus preventing any possible friction against the inner wall of the outlet 33. At the same time 55 the washer 54 being compressed by the nut 42 the washer 54 exerts a pressure against the nut 42 and acts as a lock-washer to hold the nut firmly in place so that the nut 42 cannot become loosened from vibration. This same effect is produced on all outlets where a conical washer 54 is used.

As shown in Figures 1 and 2 some of the conduits 41 are shorter than others, for the reason that one set of conduits 41 must lead around the 65 cylinder blocks 22 to the spark plugs on the far side thereof. In order to retain the conduits 41 in position clips 55 and 56 are used, as best shown in Figures 11, 12 and 13. The clips 55 are used to hold the conduits 41 to the push-rod casings 23 70 and comprise a single strip of spring metal, the center portion 58 of which is bent upon itself to surround the conduit 41. A bolt 59 having a nut 60 is disposed through the clip 55 adjacent the conduit 41 to hold the bent portion 58 securely 75

on the conduit 41. The opposite portions of the clip 55 are curved as shown at 61 to surround the push-rod casings 23 and the ends 62 are flared or turned outward. With this construction, when it is desired to remove the conduit 41, it is only necessary to pull the conduit 41 and the spring clip 55 will bend sufficiently to release the push-rod casings 23. In replacing the conduit 41 the flared ends 62 will force the clip 55 open so that it may be easily slipped on and off of the push-rod casing 23.

The clips 56 are used to hold the conduit 41 to one of the cooling fins 57 of the cylinder block 22. The clip 56 comprises a single strip of spring metal bent upon itself at 63 to surround the conduit 41, with the ends 64 adjacent one cooling fin 57. A bolt 65 passes through the end 64 and the fin 57 and is secured by a nut 66. In removing the conduit 41 it is necessary only to remove the bolt 65, allowing the clip 56 to remain on the conduit 41.

From the outlets 33 the conductors 39 surrounded by the conduits 41 lead to the spark plugs of the motor. If a shielded spark plug such as shown in Figures 3 and 8 is used the conductor 39 is attached to the plug 67 and the conduit 41 connected to the shielding of the plug. However, it is common to use ordinary unshielded spark plugs 68 and for this purpose a shield is provided to be used with such unshielded plugs, as best shown in Figures 9 and 10. The hereinafter described shield is made so that it may be used with any standard make of unshielded plug without the necessity of changing the shielding means. The spark plug shield (as best shown in Figures 9 and 10) is designated generally as 69 and comprises an open-bottomed cup 70 adapted to surround the spark plug 68. The cup 70 may be made longer or shorter to accommodate various types of unshielded plugs 68. The cup 70 is provided with an inwardly tapered bottom portion 71 so that it may be easily seated on the cylinder head of the engine. The tapered portion 71 terminates in an inturned annular flange 72. The flange 72 is adapted to abut the lower skirt of the plug 68. A copper washer 73 may be secured inside the cup 70 above the flange 72 so as to insure sealing contact of the plug 68 with the cylinder head of the engine. The cup 70 is made sufficiently large to allow a socket wrench to be used to screw the plug 68 firmly into place. When the plug 68 is screwed into place the cup 70 will be rigidly held thereabout, and in electrical contact with the engine. On the upper edge of the cup 70 an annular projecting flange 74 is provided by bending the metal upon itself and a supporting shoulder 75 is formed by bending the metal of the cup 70 outward and downward. Before the end 76 of the cup 70 is turned inward as shown in Figure 10 an annular L-shaped band of steel or other metal is placed in the housing formed by bending the cup 70 and the end 76 is then bent inward to hold the ring 77 in place. With this construction a firm foundation is provided for the shoulder 75 with the use of the least possible material so as to reduce the weight.

Disposed over the cup 70 is a cap 78 formed or moulded of dielectric material such as Bakelite. The cap 78 is electro-plated or otherwise covered with metallic foil or other conductive means 79 to protect the cap 78 and also to serve as an electrical conductor. On the lower end of the cap 78 is formed an annular depending flange 80 with a recess 81 adjacent thereto. A special compound washer 82 is disposed in the recess 81 so that

when the cap 78 is disposed on the cup 70 the flange 74 on the cup 70 will ride against the washer 82 to make a moisture-proof seal. At the same time the depending flange 80 on the cap 78 will be in electrical contact with the shoulder 75 on the cup 70. A re-inforcing member 83 is disposed in the top of the moulded cap 78.

On one side of the cap 78 is disposed a screw-threaded bushing 84 the inner face of which is beveled as shown at 85 to receive the tapered face of a conical washer 54. The portion of the cap 78 adjacent the conical washer 54 is also beveled so that the washer 54 will make a sealing contact against the cap 78 and the bushing 84. The usual collar nut 42 is used to hold the conduit 41 to the bushing 84.

Through the center of the bushing 84 and through the cap 78 is an opening 86 to accommodate the conductor 39 with the insulation 40. The opening 86 is made at an angle to the spark plug 68 so that the conductor 39 and conduit 41 will not be bent between the outlet 33 on the manifold 25 and the spark plug shield 69. The conductor 39 is usually made of strand wire and the ends of the strands of the conductor 39 are formed into one piece by solder 87, for the purpose hereinafter shown.

Set in the moulded cap 78 immediately above the spark plug 68 is an interiorly screw-threaded bushing 88. A screw 89 is disposed through the bushing 88 and is provided with a sharp point 90. The point 90 of the screw 89 is adapted to be forced through the insulation 40 and make contact with the conductor 39. The ends of the conductor 39 being held together by the solder 87, the point 90 will spread the strands of wire as it is forced through and will insure a good electrical contact.

Carried by the lower end of the screw 89 is a coil spring 91. The upper end of the coil spring 91 may be soldered to the screw 89 and the lower end of the spring 91 is adapted to make contact with the stem of the spark plug 68.

The cap 78 being formed of dielectric material such as Bakelite, a short dependent skirt 92 is provided adjacent the upper portion of the spark plug 68 and a second longer skirt 93 is provided adjacent the wall of the cup 70. The skirt 92 serves as a container for the spring 91.

The skirts 92 and 93 are adapted to prevent high tension flashes from the spark plug 68 to the cup 70. In flying at high altitudes in rarefied air these flashes will occur very frequently unless some means such as the skirts described are used to prevent them. With the spark plug shielding means here described it has been found very successful to fill the spaces in the cup 70, designated generally as 98, with a petroleum jelly. This is made possible by reason of the fact that the cup 70 and the cap 78 are entirely moisture-proof and will retain the petroleum jelly therein. By this method the flashes from the plug to the cup 70 are eliminated and a cooling means is afforded for the spark plug.

The cap 78 is held onto the cup 70 by means of a spring bail 94 the ends of the bail 94 being disposed through the shoulder 75 and the ring 77. In screwing the spark plug 68 into position the cup 70 will be turned around and the bail 94 will not always be in proper position to hold down the cap 78. Therefore, a series of openings 95 are provided so that the bail 94 may be placed in any desired position. The ring 77 acts as a bearing for the bail 94 and prevents the distortion of the openings 95 by the bail 94. At the

top of the bail 94 is provided a ball 96 which is free to rotate on the bail 94. When the cap 78 is placed on the cup 70 the spring 91 is compressed and exerts tension against the cap 78. The ball 96 is provided on the bail 94 so that the bail 94 may be easily swung to the top of the cap 78 and seated in a recess 97 provided therefor. With this construction the bail 94 will at all times hold the cap 78 firmly on the cup 70 but will allow the cap 78 to be quickly removed at any time.

In aircraft practice dual ignition systems are often used. Therefore, two magnetos 99 and 100 are provided to supply electrical impulses to their respective series of spark plugs. In order that the wires from the spark plugs may lead to the magnetos, outlets 101 and 102 are provided on the manifold 25. These outlets 101 and 102 are similar to the outlets 33 except that they are much larger in that several wires have to pass therethrough. These outlets may be placed at any point on the manifold 25, depending upon the type of motor used and the contour of the manifold 25. From the outlets 101 and 102 conduits 103 and 104 lead to the two magnetos. The conduits 103 and 104 are similar in construction to the conduits 41 but are made larger to accommodate more wires. The magnetos 99 and 100 are usually located behind the engine so that the conduits 103 and 104 lead from the manifold 25 over the engine and are held to the engine by clips 105 similar in construction to the clips 56. The conduit 103 terminates in an elbow 106 on the magneto 99 and the conduit 104 terminates in an elbow 107 on the magneto 100.

Since the mode of connecting the conduits 103 and 104 to the outlets 101 and 102 is the same as the connection between the conduits 103 and 104 and the elbows 106 and 107 only the connection to the elbow 107 will be described. This connection is best shown in Figures 5 and 6. A ferrule 108 is disposed over the end of the conduit 104 and has its inner end 109 turned inside of the conduit 104 so as to present a smooth interior surface for the conductors 39. A collar 110 is secured by braising or other means on the ferrule 108. A collar nut 111 is provided on the conduit 104 similar to the collar nuts 42 heretofore described. The elbow 107 is provided with a threaded neck 112 onto which the collar nut 111 is screwed.

A rubber gasket 113 is disposed in the elbow 107 where said elbow 107 enlarges to form the neck 112. The ferrule 108 is forced against the gasket 113 and is held in place by the nut 111, thus making a moisture-proof joint. At the same time the ferrule 108, the collar 110 and the nut 111 acting on the neck 112, continue the electrical circuit desired. The elbow 107 is provided with an annular projecting shoulder 114 near its lower end, from which shoulder 114 depends an annular flange 115. Two-piece covers 116 are provided to cover the exposed portions of the magnetos 99 and 100. The lower end 117 of the elbow 107 extends into the upper part of the two-piece covers 116 and is provided with an annular groove 118. The upper part of the covers 116 is provided with bosses 119 from which projects a flange 119a. The flange 119a interlocks with the flange 115 on the shoulder 114 of the elbow 107, making a moisture-proof enclosure. Disposed through the bosses 119 are bolts 120 operating with nuts 121 to hold the two-piece covers 116 firmly together. On one cover plate 116 is

disposed a boss 122 which carries a set-screw 123. The set-screw 123 projects into the groove 118 on the elbow 107 and prevents the removal of the elbow 107 from the cover plates 116.

Inasmuch as the magnetos on various types of engines may be in various positions, the groove 118 is annular so that the elbow 107 may be placed in the cover plates 116 from any position. Disposed on the inside of each cover plate 116 is a leaf-spring 124 secured at one end to the cover plates 116 by rivets or other suitable means 125. When the cover plates 116 are forced against the magnetos 99 and 100 the springs 124 will hold the cover plates 116 under tension and thus reduce vibration and wear.

The elbow 107 is provided with several outlets 126. These outlets 126 are similar to the outlets 33 on the manifold 25. Conduits 127 lead from the outlets 126. The conduits 127 are similar in construction to the conduits 41, but are made slightly larger so that one or more wires may be carried therethrough. The conduits 127 are provided with ferrules 50 and collar nuts 42 and the connections to the outlets 106 are the same as the connections to the manifold 25 heretofore described. One conduit 127 leads to the starting or booster magneto 128 and another conduit 127 leads to the switch 129. As shown in Figures 15 and 16 the conduits 127 may lead to the junction box 130. The junction box 130 is formed of a piece of seamless metal tubing and is provided with outlets 131 similar to the outlets 33 heretofore described. The ends of the conduits 127 that enter the starting magneto 128 and the switch 129 may be made with merely a ferrule 132 adapted to be frictionally held in place by clamps 133 on the switch 129 and the magneto 128. This construction is optional but inasmuch as the switch 129 and the magneto 128 are usually mounted on the instrument panel of the aeroplane, there is very little danger of these terminals becoming wet and they are not subject to the strain that the other connections heretofore described are subjected to.

As shown in the lower portion of Figure 6, the ends 87 of the conductors 39 may be provided with indicia. By having the ends of the wires numbered it is possible to quickly assemble the wiring in the shielding means without having to check each wire to find out where it should go.

In order to have the ignition system entirely shielded it is necessary to have the magnetos and switch shielded. This is accomplished by first insulating and then enclosing the parts in a continuous metal casing. When the switch or the magnetos are secured to the frame or body of the aeroplane the casings will act as a conductor. In the ordinary magneto illustrated the operating parts are protected in the main by a metal casing which partially serves as a shield so that it is only necessary to add the cover plates 116 to form a complete shield for the magnetos.

As pointed out heretofore one of the objects of this invention is to provide a system which will decrease the resistance in the high tension conductor used. In ordinary wiring systems separate wires are run from each spark plug to each magneto and from each magneto to each starting or booster magneto, and from each of the three magnetos to the switch. By the use of the junction box 130 the length of wire necessary to make the circuits is materially reduced. Therefore, the resistance in the wires is reduced and the ignition system will work with much greater efficiency.

As to the shielding properties, it will be seen

that if any electrical radiations are released anywhere between the magnetos and the spark plugs such radiations will immediately be absorbed and grounded to the engine or fuselage of the airplane. Similarly, any electrical radiations coming from the outside will be absorbed and grounded before they can interfere with the ignition. From the foregoing it will be seen that interference with the radio reception and equipment by 10 the ignition system is eliminated.

It is known in aircraft practice that there are sources of disturbance of radio reception other than that directly produced by the ignition system. Even with the generator magneto cut-off 15 there may be currents produced, and the broad idea of the invention described is to effectively bond and shield all of the parts so that a continuous electrical conductor is afforded between all metal parts to ground. Unless this is done 20 there is varying resistance between moving, poorly bonded, or between rubbing or vibrating metal parts which causes interference and noises in the radio receiver. Such interference and disturbance may even be caused by the sparking of a 25 vibrating type voltage regulator used on the generators. To effect elimination of this it is desirable and necessary to enclose in highly conductive casings all parts carrying current of any description and to properly and securely bond at 30 intervals to the aircraft such parts in order to obtain efficient uninterrupted radio reception.

Having thus fully described the invention what is claimed as new and desired to be secured by Letters Patent is:

35 1. A radio shielding system for both the high and the low tension portions of the entire ignition system of an internal combustion engine comprising a rigid manifold to enclose a plurality of wires, flexible conduits enclosing wires from the 40 rigid manifold to the spark plugs, conductive housings around all of the operating units of the ignition system and conduits enclosing wires interconnecting units of the ignition system.

2. A radio shielding system for both the high 45 and the low tension portions of the entire ignition system of an internal combustion engine comprising a rigid manifold to enclose a plurality of wires, flexible conduits enclosing wires from the rigid manifold to the spark plugs, conductive 50 housings around all of the operating units of the ignition system and conduits enclosing wires interconnecting units of the ignition system, the manifold and the several conduits being electrically connected and grounded.

55 3. A radio shielding system for both the high and the low tension portions of the entire ignition system of an internal combustion engine comprising a rigid manifold to enclose a plurality of wires, flexible conduits enclosing wires from the 60 rigid manifold to the spark plugs, conductive housings around all of the operating units of the ignition system, conduits enclosing wires interconnecting units of the ignition system, the manifold and the several conduits being electrically 65 connected and grounded and means to bond the flexible conduits to the engine.

4. In a radio shield for the ignition system of an internal combustion engine, a manifold to enclose a plurality of ignition wires and a plurality 70 of outlets on said manifold, said outlets being flared outwardly adjacent the manifold.

5. In a radio shield for the ignition system of an internal combustion engine, a manifold to enclose a plurality of ignition wires and a plurality 75 of outlets on said manifold, said outlets being

flared outwardly adjacent the manifold, one portion of said outlets being flared more than other portions.

6. In a radio shield for the ignition system of an internal combustion engine, a manifold to 5 enclose a plurality of ignition wires, a plurality of outlets on said manifold, said outlets being flared outwardly adjacent the manifold and conduits connected to the outlets and extending to the spark plugs of the engine. 10

7. A radio shielding system for both the high and the low tension portions of the entire ignition system of an internal combustion engine comprising a rigid manifold to enclose a plurality of ignition wires, flexible conduits to enclose 15 some of the ignition wires and junction boxes connected to some of the flexible conduits.

8. A radio shielding system for both the high and the low tension portions of the entire ignition system of an internal combustion engine comprising a rigid manifold to enclose a plurality of ignition wires, flexible conduits to enclose 20 some of the ignition wires and junction boxes connected to some of the flexible conduits to decrease the electrical capacitance of the shielding system 25 by decreasing the length of conduits necessary to interconnect the several magnetos and switch.

9. In a radio shield for both the high and the low tension portions of the entire ignition system of an internal combustion engine, a rigid 30 manifold and a plurality of flexible conduits to enclose all of the wires of the ignition system, said members being electrically connected but readily separable to permit replacement of one or more members. 35

10. In combination with a radial aviation engine provided with magnetos, spark plugs and a propeller, a radio shielding means for both the high and the low tension portions of the entire ignition system comprising a rigid manifold disposed in front of the engine behind the propeller, said manifold being adapted to enclose and shield a plurality of ignition wires, a relatively large conduit extending over the engine to enclose and shield wires between a magneto and the manifold, 40 flexible conduits to enclose and shield wires between the manifold and the spark plugs, conductive coverings around all of the operating units of the ignition system and flexible conduits to enclose and shield wires interconnecting 45 the operating units of the ignition system. 50

11. In combination with a radial aviation engine provided with magnetos, spark plugs and a propeller, a radio shielding means for both the high and the low tension portions of the entire 55 ignition system comprising a rigid manifold disposed in front of the engine behind the propeller, said manifold being adapted to enclose and shield a plurality of ignition wires, a relatively large flexible conduit extending over the engine to 60 enclose and shield wires between a magneto and the manifold, relatively small flexible conduits to enclose and shield wires between the manifold and the spark plugs, conductive coverings around all of the operating units of the ignition system and flexible conduits to enclose and shield wires 65 interconnecting the operating units of the ignition system.

12. In combination with an internal combustion engine having magnetos, booster magneto, spark plugs and switch, a radio shielding system for both the high and the low tension portions of the entire ignition system comprising a main manifold adapted to enclose a plurality of igni- 70

tion wires, a conduit connecting a magneto and the manifold and enclosing wires therebetween, flexible conduits enclosing wires from the manifold to the spark plugs, shielding coverings on the magnetos, booster magneto and switch, and flexible conduits enclosing wires interconnecting the magnetos, booster magneto and switch.

13. In combination with an internal combustion engine having magnetos, booster magneto, spark plugs and switch, a radio shielding system for both the high and the low tension portions of the entire ignition system comprising a main manifold adapted to enclose a plurality of ignition wires, a conduit connecting a magneto and the manifold and enclosing wires therebetween, flexible conduits enclosing wires from the manifold to the spark plugs, shielding coverings on the magnetos, booster magneto and switch, flexible conduits enclosing wires interconnecting the magnetos, booster magneto and switch and means to connect the flexible conduits to shielding of the spark plugs.

14. In combination with an internal combustion engine having magnetos, booster magneto, spark plugs and switch, a radio shielding system for both the high and the low tension portions of the entire ignition system comprising a main manifold adapted to enclose a plurality of ignition wires, a conduit connecting a magneto and the manifold and enclosing wires therebetween, flexible conduits enclosing wires from the manifold to the spark plugs, shielding coverings on the magnetos, booster magneto and switch, flexible conduits enclosing wires interconnecting the magnetos, booster magneto and switch and means to connect the flexible conduits to shielding of the spark plugs, all of the elements of the shielding system being connected to form a continuous shield but each element being readily separable from the others to permit replacement of individual elements.

15. In a radio shielding means for the ignition system of an internal combustion engine, including spark plugs, magnetos with distributor blocks and high tension cables, said shielding means comprising a metallic casing means to cover and enclose the normally exposed distributor blocks, said casing including a rotatable elbow formation through which said cables are directed for connection with the spark plugs.

16. A radio shielding means for both the high and low tension sides of the entire ignition system of an internal combustion engine comprising sectional, rigid manifolds to enclose and electrically shield a plurality of ignition wires, flexible conduits connected to the manifolds to enclose one or more ignition wires leading to the spark plugs and additional flexible conduits

to enclose and electrically shield low tension wiring of the ignition system.

17. A radio shielding means for both the high and low tension sides of the entire ignition system of an internal combustion engine comprising 5 sectional, rigid manifolds to enclose and electrically shield a plurality of ignition wires, flexible conduits connected to the manifolds to enclose one or more ignition wires leading to the spark plugs, radio shielding on the spark plugs, and 10 additional flexible conduits to enclose and electrically shield low tension wiring of the ignition system.

18. A radio shielding means for both the high and low tension sides of the entire ignition system 15 of an internal combustion engine comprising sectional, rigid manifolds to enclose and electrically shield a plurality of ignition wires, flexible conduits connected to the manifolds to enclose one or more ignition wires leading to the spark plugs, 20 radio shielding on the spark plugs, said flexible conduits being connected to the shielding of the plugs and additional flexible conduits to enclose and electrically shield low tension wiring of the 25 ignition system.

19. A radio shielding means for both the high and low tension sides of the entire ignition system of an internal combustion engine comprising sectional, rigid manifolds to enclose and electrically 30 shield a plurality of ignition wires, flexible conduits connected to the manifolds to enclose one or more ignition wires leading to the spark plugs, radio shields enclosing the spark plugs, said flexible conduits being connected to said radio shields on the plugs and additional flexible conduits enclosing 35 and electrically shielding wires interconnecting various units of the ignition system.

20. A radio shielding means for the entire ignition system of an internal combustion engine, said system including magnetos, spark plugs and 40 switches, comprising complementary cover plates to enclose the normally exposed distributor blocks of a magneto, a rotatable elbow associated with the cover plates through which ignition wires pass from the magneto, a rigid manifold to receive a 45 plurality of wires from the rotatable elbow, shielding means surrounding the wires between the rotatable elbow and the manifold, flared, projecting outlets on the manifold through which wires extend to spark plugs, flexible conduits enclosing 50 the wires between the manifold and spark plugs, radio shielded spark plugs, said flexible conduits being connected to the shielding of the plugs, metallic casings around the switch and starting magneto and flexible conduits enclosing 55 wires interconnecting the several magnetos and switch.

JOSEPH J. MASCUCH.
